his attorney.

UNITED STATES PATENT OFFICE.

THOMAS DODDS, OF BANKSVILLE TOWNSHIP, ALLEGHENY COUNTY, PENNSYLVANIA,
ASSIGNOR OF ONE-HALF TO FRANK E. ADAMS, OF DORMONT, PENNSYLVANIA.

HEADLIGHT FOR MOTOR VEHICLES.

Application filed September 28, 1927. Serial No. 222,451.

To be satisfactory, the headlights must properly illuminate the road in front of the vehicle but they must not cause a glare in the eyes of drivers of vehicles approaching from 5 the opposite direction.

The expediency of dimming one's headlights when about to pass another vehicle is objectionable since the sudden diminution of the light is confusing, as the eyes accommodate 10 date themselves slowly thereto especially in the case of mature drivers or those having defective eyesight.

The object which I have in view is the elimination of the glare without sacrificing road- 15 way illumination.

I accomplish this result by providing the headlight, in addition to the usual concaved reflecting surface below and at the sides of the lamp, a horizontal reflecting surface above 20 the lamp and a shield to prevent the forward projection of the rays from the lamp filament.

The specific embodiment of my invention illustrated in the drawings is characterized 25 by the employment of a shield, preferably mounted on the lamp socket and which provides a flat reflecting surface disposed in a horizontal plane above the lamp and a downwardly, and preferably outwardly inclined 30 shield in front of the lamp filament.

Referring to the drawings, Fig. 1 is a front elevation of the headlight; Fig. 2 is a vertical section of the same; Fig. 3 is a horizontal section of the same, and Fig. 4 is a plan view of 35 the sheet metal blank from which the shield is formed.

Referring to the drawings, 1 is a conventional type of head light casing having an interior concaved reflecting surface 2. 3 is the 40 lamp socket and 4 the electric bulb which is inserted therein. It is now the general practice to employ an expandible socket into which the bulb is inserted.

5 is a shield which may be a piece of sheet 45 metal having bright reflecting surface, such for instance as tin. The front edge of the shield 5 is straight while its rear and side is provided with a continuous curved edge de- 50 signed to fit against the reflecting surface 2 as shown in Figs. 1 and 3. At its rear the shield

is provided with a tongue 6 which is provided with a circular hole 7 and which is bent down vertically so as to be slipped over the socket 3, the hole 7 being of proper size so that the expansion of the socket by the insertion of the 55 bulb will bind the shield in position. At the front the shield 5 is provided with a cut out tongue 8 which is bent downwardly, and preferably inclined slightly forwardly. The tongue 8 forms a shield which depends in 60 front of the lamp filament and thus prevents the rays therefrom being directed directly forward. The surface of the tongue 8 being of reflecting character throws the direct rays rearwardly against the reflecting surface 2. 65

It is obvious that the rays of light which would otherwise be reflected by the upper portion of the reflecting surface 2 will be reflected downwardly by the under surface of the shield 5 and will thus not be thrown forwardly and upwardly as at present. Again the rays will not be thrown directly forward from the lamp filament. Again the full reflective effect of the sides and bottom of the reflecting surface 2 are utilized. 75

In using my shields in connection with standard headlights, I have found that the illumination of the roadway is perfect but there was absolutely no glare in the eyes of approaching drivers. Indeed frequently 80 drivers of approaching cars have dimmed their lights, thinking that my headlights had been dimmed.

My invention may be incorporated as an improvement in headlights when the latter 85 are manufactured or my invention may be readily and at trifling expense applied to headlights already in use.

What I desire to claim is:—

As a new article of manufacture, a lamp 90 shield for automobile headlights formed from a flat piece of material having a body of seg- 95 mental contour, the front edge of the body being straight and the remaining edge of the body being arcuate to fit the reflector of a lamp above and closely adjacent the lamp bulb, said plate further having a tongue pro- 100 jecting centrally from the arcuate side of the body and provided with an opening to fit over a lamp socket, the tongue being bent at

substantially right angles to the body, said plate further having a pair of slits extending inwardly from the front straight edge on opposite sides of the center to define a second tongue, said second tongue being bent angularly with respect to the body and extending from the body in the same general direc-

tion as the first tongue, said second tongue being imperforate throughout and forming an opaque shield closely adjacent the front 10 of the lamp bulb.

Signed at Pittsburgh, Pa., this 26th day of Sept., 1927.

THOMAS DODDS.
